United States Patent Office.

FREDERICK J. MILLER, OF BROOKLYN, NEW YORK.

Letters Patent No. 61,947, dated February 12, 1867.

IMPROVED CASTER-FRAME.

The Schedule referred to in these Letters Patent and making part of the same.

TO ALL TO WHOM IT MAY CONCERN:

Be it known that I, FREDERICK J. MILLER, of Brooklyn, in the county of Kings, and State of New York, have invented, made, and applied to use, a certain new and useful Improvement in Caster-Frames; and I do hereby declare the following to be a full, clear, and exact description of the said invention, reference being had to the annexed drawing, making part of this specification, wherein—

Figure 1 is a front view of said caster-frame.

Figure 2 is a plan of the base of the caster-frame.

Figure 3 is a front view of the handle; and

Figure 4 is a side view of the handle.

Similar marks of reference denote the same parts.

The object of my invention is to produce a caster-frame suitable for hotels, dining-rooms, and other public places, having the base provided with receptacles for holding salt, sugar, &c., and at the same time arrange the handle so as to hold a bill of fare.

In the drawing, *a* is the base of the caster-frame, provided with any number of compartments, *b*, with openings *c* into the same; *d* the band for receiving the bottles; *e* is the handle to which is affixed a spring, *f*, for holding a bill of fare.

To enable others to make and use my said improvement, I will proceed to describe the construction and operation of the same.

The base *a* is to be of any desired character, according to the style of caster, and has openings cut into the same, as seen at *c*, the base having an inside bottom, and is partitioned off according to the number of compartments required, and the said base, which formerly occupied a great deal of room on the table to no purpose, can be used for holding salt, sugar, &c., the receptacles formerly used for that purpose being dispensed with entirely. On the handle *e* I provide a spring, *f*, for receiving and holding the bill of fare, as shown in fig. 3, and the position of said spring or holder renders it very accessible to place in or remove from it the bill of fare, and at the same time keeps it from becoming soiled and dirty.

Having thus described my said invention, what I claim, and desire to secure by Letters Patent, is—

1. I claim a caster-frame, whose base is provided with receptacles or compartments, for salt, sugar, &c., when constructed in the manner described and shown.

2. I claim the combination of the base *a*, and the spring or holder *f*, when applied to a caster-frame in substantially the manner described and shown.

In witness whereof I have hereunto set my signature this 18th day of December, 1866.

FRED. J. MILLER.
